FUEL CONTROL

Milton J. Kittler, Detroit, Mich., assignor to
George M. Holley and Earl Holley

Application March 3, 1939, Serial No. 259,596

6 Claims.

(Cl. 261—37)

The object of this invention is to control the mixture ratio of an airplane engine of the variable Venturi type in which the fuel is discharged into the throat of a variable venturi formed between two streamlined throttles. In a carburetor of this type, as the throttle valves are opened, the depression in the venturi decreases, whereas in the normal type of carburetor, when the throttle is opened, the depression in the venturi increases.

I have discovered that I can utilize the variable depression in the throat of such a variable Venturi carburetor as the controlling factor on the pressure of the fuel in the fuel supply chamber, so that I can utilize the depression in the venturi to maintain the mixture ratio constant when the altitude varies and also when the load varies due to change in the pitch of the propeller, at any given position of the variable Venturi throttles.

In the drawings:

Figure 1 shows diagrammatically the preferred arrangement of the parts.

Figure 2 shows the desired fuel/air mixture ratios at various rates of air flow measured in pounds per hour.

Figure 3 shows a detail, being a cross sectional elevation taken on plane 3—3 of Figure 1.

Figure 4 shows a cross-section taken on plane 4—4 of Figure 3.

In Figure 1, 10 is the aneroid bellows which is substantially exhausted of air so that it can respond to variations of pressure in a chamber 23 which is connected to an air and fuel passage 30 (which communicates freely with the variable venturi) through the passage 54 so as to be subjected to the depression in the throat of the venturi formed between the throttles 43 and 44. The bellows 10 carries an ear 11 which engages with the pin 12 on a lever 13 pivoted at 14, the pivot 14 being located in a rod 15 which is adjusted by a knurled screw 16.

The lever 13 terminates in a pin 17 which engages between the jaws of a bracket 18 which moves a slide valve 21. The movement of the valve 21 is determined by a calibrated spring 14 supported on an adjustable seat 13. This slide valve 21 controls the area of a slot 22 which communicates with the passage 24 which is connected to the air chambers 25, 26 between which are located the diaphragms 19 and 20, which between them enclose the fuel supply chamber 27. The Venturi suction in the chamber 23 is thus applied to the diaphragms 19 and 20 and

thus controls the pressure of the fuel in the fuel chamber 27.

The air chambers 25 and 26 are connected with each other through a passage 28. The chambers are also connected with the main air entrance 15 of the carburetor, communicating with the vent ring 90 through a pipe 31. The area of a restriction 71 in the pipe 31 thus determines the depression in the chambers 25 and 26 and thus determines the fuel flow as the pressure in 10 25 and 26 is intermediate the pressure in the air entrance 15 and in the passage 30.

Fuel is supplied to the diaphragm chamber 27 by a fuel pump 32 which supplies fuel through a venturi 33 which delivers fuel to the needle valves 34 and 35. The fuel supplied by the fuel pump 32 is maintained at a substantially constant pressure by means of a diaphragm bellows 36, and a pressure relief valve 37.

As the fuel flows through the venturi 33 it causes a pressure drop which reflects the quantity of fuel taken into the diaphragm chamber 27. This fuel flow causes differential pressures which operate the diaphragm 38 located in a chamber 78 and overcome the spring 77, and thus moves a needle valve 39, which supplies fuel under pressure to the passage 40 which discharges into the passage 41 which is in free communication with the atmosphere through the opening 91, and discharges down the passage 42 into the throat of the variable venturi formed between the throttles 43 and 44.

The main fuel needle valve 29 is moved by the throttle 44 by means of the arm 68 and the ball 35 end 69. The lever 68 is held in contact with a cam 65 by a spring 81. The two throttles 43 and 44 are geared together by means of the gears 45 and 46 and are operated by the gear 80, which gear is integral with the cam 65. The needle valve 29 is provided with a central air passage 47 which supplies air for idling to the air and fuel passage 30. This idle air enters through the air entrance opening 48 to the annular passage 49 which communicates with the passage 47. When the throttles are closed the needle valve 29 acts as a valve to admit air to the passage 30. In addition to the air for idling, an opening 50 forms a permanent vent to the nozzle passage 30.

In order to provide a lean mixture for cruising, the manual control valve 51 is provided operated by a lever 52. This valve carries an opening 53 and the valve is shown in the lean position so that the port therein is located in the passage 54 communicating with the fuel and air

passage 30. The application of a portion of the nozzle suction as determined by the relative size of the restricted openings 53 and 71 to the air chambers 25 and 26 through the passage 53 regulates the fuel flow in a well known manner. The pressure in the chamber 25 adjacent to the diaphragm 19 and the chamber 26 which communicates with the chamber 25, adjacent to the diaphragm 20, regulates the relative pressure of the fuel in the chamber 21. This method of regulating the pressure in the air chambers 25 and 26 is the method that has been in use for years as the means for obtaining the lean mixture customarily used when cruising. The effect of bleeding air to the nozzle passage 30 is incidental and of no material consequence. This port communicates with the chamber 55 through the outlet 56. The chamber 55 is also connected with the passage 24 which communicates with the air chambers 25 and 26. The chamber 55 is bounded on either side with diaphragms 57 and 58 and these diaphragms in their turn form the walls of fuel chambers 59 and 60. These two fuel chambers communicate with the entrance and the throat of the venturi 33, the chamber 59 connecting with the throat of the venturi 53 through the passage 61, the chamber 60 communicating with the fuel entrance 63 to the venturi 33 through the passage 62.

A valve seat 66 on a bridge 67 is carried by both diaphragms 57 and 58, the bridge 67 connecting the two diaphragms 57 and 58 together and carrying the valve seat 66 which is adapted to close the passage 56 whenever the velocity of flow through the venturi 33 exceeds the value determined by a spring 72. Any increase in fuel flow through the throat 33 of the small fuel venturi above the flow determined by the spring 72 causes the diaphragms 57 and 58 to move over to the left and thus move the disc 66 and thus close the passage 56. Thereafter, the effect of the suction in 30 acting through the restricted passage 53 is eliminated and the effect of the air pressure in the air entrance 80 which is transmitted through the pipe 31 is not modified by the nozzle suction which is transmitted through the passage 54. The mixture ratio therefore becomes richer when the fuel flow exceeds the value determined by the pressure of the spring 72 and this is the cause of the abrupt change in the mixture ratio indicated by the line B—C of Figure 2.

The spring 72 unseats the valve seat 66 by moving the bridge 67 to the right, and the bridge moves to the left under the influence of the fuel flow through the venturi 33. As the valve 66 seats it is held on its seat by the vacuum in the pipe 54, which vacuum prevents "hunting" of the valve 66.

The pressure of the fuel in the chamber 27 is also partially controlled by the tension spring 78 which tends to draw the two diaphragms 20, 19 together.

Assuming that the plane is in the air having just left the earth and flying with the valve 51 adjusted, as shown in Figure 1, in the cruising lean position, then as the throttles 43, 44 move to the closed position, an increase in suction is developed in the variable venturi between the two throttles 43 and 44, and therefore in the passage 30. This high suction is reflected in the high suction created in the passage 54 which communicates through the restriction 53 through the passage 56 to the chamber 55, and communicates with the passage 24 which imposes a relatively

high suction on the diaphragms 19 and 20. The actual suction is determined by the relative size of the opening 53 and of the restriction 71 in the passage 31. If this restriction 71 is made very large, the mixture would be relatively rich, and if this restriction 71 is made very small, the mixture is relatively lean. Hence the size of the restriction 71 determines the fuel economy.

As the engine ascends into the air the bellows 10 opens, the valve 21 rises and gradually uncovers the slotted opening 22. The nozzle suction existing in the chamber 23 is thus transmitted to the passage 24 so that as the plane ascends into the air, the mixture does not become richer, despite the fall in density of the air. The characteristic of a variable Venturi carburetor is such that the suction in the conduit 54 can never become very slight and is always at a considerable pressure below the atmospheric pressure, but of course as the atmospheric pressure falls the pressure in 54 also falls, keeping in step with the fall of the atmospheric pressure. The pressure of the atmosphere surrounding the diaphragm 10 is therefore determined by two factors: (1) the pressure of the atmosphere; (2) the velocity effect of the variable venturi formed between the two throttles 43 and 44. The pressure in 23 is that amount below atmospheric pressure that is determined by the air velocity which is determined by the throttle opening. The only time the suction in 54 is slight is when operating at less than 20% of power, when close control of the mixture ratio is unimportant. If the pitch of the propeller is reduced, so that the speed of the engine increases for a given throttle position, and the flow through the variable venturi increases to such a point that the density of the air in the throat falls appreciably, there is again an increase of suction in the nozzle passage 30, which is transmitted to the chamber 23 and causes a further opening of the slot 20 and thus causes a further reduction in the pressure in the chambers 25 and 26 acting on the diaphragms 19 and 20, and thus still further reduces the fuel consumption.

Thus, if the density of the air in the throat of the venturi falls either because of an increase in altitude or a decrease in pitch, the mixture remains substantially constant. As the engine approaches sixty per cent (60%) of its rated fuel supply there comes a time when there is a critical pressure differential between the throat of the venturi 33 and the approach to the venturi. At the time of this critical velocity, the spring 71 in the chamber 78 and the spring 72 in the chamber 59 yield, and in one case the needle 39 is opened to admit additional fuel to the passage 48 and at the same time, the valve 66 controlling the opening leading to 56 is closed. There is thus an abrupt increase in the mixture ratio due to the lessened effect of nozzle suction from the passage 30 acting on the diaphragms 19 and 20 as the suction effect acting through the restriction 53 is eliminated, and also due to the fuel admitted by the needle valve 39.

For all practical purposes, the manual control 53 is thereafter out of action until the throttles are once more closed and the fuel supply reduced, whereupon the mixture ratio immediately and automatically goes back to the cruising lean value determined by the relative size of the restriction 53 and the restriction 71.

The net result of these various devices is that if the mixture ratio, Figure 2, is at A with an air flow of twenty per cent (20%) of maximum and remains at the same figure at the point B when

the air flow is sixty per cent (60%) when it abruptly jumps to the mixture ratio C due to the closing of the valve seat 66 on the opening leading to the passage 56, and then as the needle 39 continues to open so as to admit more and more fuel to the passage 48, the mixture ratio is increased along the line C—D. The point B at which the mixture ratio takes the abrupt jump from B to C is sixty per cent (60%) of the maximum horsepower of the engine as air flow and horsepower are substantially equivalent to each other at this end of the horsepower range.

If the valve 51 is moved, so as to disconnect the restriction 53 and completely block the flow through the passage 54, then the mixture ratio at twenty per cent (20%) of maximum horsepower is at A' and remains at this mixture ratio until the point C is reached, at which time the valve 39 opens and the mixture ratio becomes progressively richer, as shown at the rising line C—D. The valve 39 therefore is responsible for the portion of the curve C—D and the valve 66 is responsible for the portion of the curve B—C. The fact that this mixture ratio diagram remains constant at all altitudes is due to the mechanism contained in the chamber 23. This device also is responsible for the fact that this diagram remains unchanged regardless of any change in the pitch of the propeller.

What I claim is:

1. In a carburetor having an air entrance, an air throttling means, adapted to form a variable Venturi passage, an air vented fuel nozzle discharging into the throat of said variable venturi, said nozzle having a restricted communication with the air entrance and a relatively unrestricted fuel and air outlet into the throat of said variable venturi, a fuel supply for said carburetor comprising a fuel pump adapted to supply fuel at a substantially constant pressure above the atmospheric pressure, a low pressure fuel supply chamber communicating with said pressure fuel supply, pressure reducing mechanism in said chamber, an air chamber associated with said fuel chamber adapted to control the pressure in said fuel supply chamber, and communicating with the air entrance of the carburetor through a restriction, a second air passage connecting said air chamber with said nozzle, a variable restriction in said passage, barometric means responsive to the absolute pressure in the air vented nozzle adapted to vary said variable restriction whereby the pressure in said air chamber associated with said fuel chamber is decreased as the absolute pressure in said nozzle decreases and is increased as the absolute pressure therein increases.

2. A device as set forth in claim 1 in which a restricted passage permits additional nozzle suction to be imposed on said air chamber throughout the cruising range, a pipe connecting said passage with said air chamber, means responsive to the fuel flow from the fuel chamber for obstructing said pipe so as to render said

restricted passage inoperative when the fuel flow to said fuel chamber exceeds a predetermined maximum fuel flow.

3. A device as set forth in claim 1 in which a restricted passage permits additional nozzle suction to be imposed on said air chamber throughout the cruising range, manual means for obstructing said restricted passage, a pipe connecting said passage with said air chamber, means responsive to the fuel flow to the fuel chamber for obstructing said pipe so as to render said restricted passage inoperative when the fuel flow to said fuel chamber exceeds a predetermined maximum fuel flow.

4. In a carburetor having a variable Venturi mixing chamber, an air entrance leading thereto, a fuel nozzle discharging into the throat of said variable venturi and responsive to the air flow therethrough, a fuel supply chamber connected to said fuel nozzle, an air chamber associated with said fuel chamber and adapted to regulate the pressure in said fuel supply chamber, a restricted passage connecting said air chamber with the air entrance, suction control means for said chamber to reduce the pressure therein comprising a second air chamber, said second chamber communicating with the throat of said variable venturi, and having a restricted communication with said first air chamber, valve means for controlling the pressure in said first air chamber so that it is intermediate the atmospheric pressure in the air entrance and the suction in said second air chamber by controlling the relative area of the restricted communication of the first air chamber with the second air chamber and with the air entrance, and means responsive to the pressure in the said second air chamber for controlling said valve means.

5. In a carburetor having an air entrance, an air passage leading therefrom, a fuel supply chamber, a fuel nozzle connected thereto and discharging into said air passage and responsive to the air flow therethrough, an air chamber associated with said fuel supply chamber and adapted to regulate the pressure in said fuel supply chamber, a restricted passage connecting said air chamber with said air entrance, a manually operated economizer valve adapted to impose a suction on the air chamber so as to counteract the effect of the atmospheric pressure in said air entrance, means responsive to the fuel flow into said fuel chamber to render said economizer valve ineffective whenever the fuel flow exceeds a predetermined maximum velocity of flow.

6. In a carburetor, an air passage, a fuel supply chamber, a fuel nozzle supplied therefrom directly responsive to the air flow through said air passage, a manually operated device for restricting the fuel supply, means responsive to the rate of fuel flow for rendering said manually operated device suddenly ineffective whenever the fuel flow exceeds a predetermined maximum.

MILTON J. KITTLER.
